ELECTRIC SWITCH

Fred Farrell, Elmwood Park, Ill., assignor to
Electrical Engineers Equipment Company, a
corporation of Illinois

Application October 15, 1935, Serial No. 45,113

6 Claims. (Cl. 200—18)

The present invention relates to electric switch-
es and has for its general object the produc-
tion of an electric switch which shall be efficient
and satisfactory in operation while being simple
in construction, economical to manufacture, and
of such design as to occupy a minimum of space
relative to its electrical capacity.

More specifically, one object of the invention is
to provide a switch wherein spring means are
employed to apply heavy pressure to the switch
contacts when contacting, and simultaneously
therewith to hold the actuating mechanism in
holding position.

Another object is to so construct and arrange
the switch contacts that they will, when engaged,
provide a novel application of balanced forces to
thereby give the high contact pressure desired.

Another object is to construct the spring means
by which the different toggle and contacting
functions are performed, in a novel way such as
to provide indications of the pressures upon the
contacts, which are being exerted at any given
time.

Another object is to utilize the spring means as
couplings between the fixed and movable parts
in such a way as to provide a floating construc-
tion for the movable parts and then to employ
self-centering contacts, the two cooperating in
the centering of the parts when the switch is
moved into closed contact engaging position.

Another object is to so construct the main
contacts of the switch that they will be related
to each other somewhat after the manner of a
ball and socket, whenever in engagement. By so
doing there will be efficient engagement whenever
the switch is closed even though the contacts may
not be in true axial alignment. Akin to this plug
and socket, or ball and socket, feature, is that
of providing substantially a line contact, so
called, between the engaging contact surfaces of
these ball and socket members in all the different
positions they may occupy when in circuit clos-
ing position.

Still another object is to combine these various
features in a structure wherein telescoping insu-
lating tubes inclose the different switch contacts.

In this connection it may be pointed out, how-
ever, that the various features of the invention
may be combined in various ways and still come
within the scope of the invention. Thus, for ex-
ample, the earlier objects may be attained with-
out employing the particular insulation provided
by telescoping insulating tubes.

Besides the various objects recited, other ob-
jects will appear as the invention is more fully
set forth. To this end reference should be had
to the following detailed description taken in
connection with the accompanying drawings,
while the scope of the invention will be more par-
ticularly set forth in the appended claims.

Before considering the drawings, it may be
pointed out that by telescoping the switch con-
tacts and by providing a plurality of line con-
tacts for each pair of mating contacts, consid-
erable saving of space for the switch structure
may be obtained. Thus if a total length of line
contact is required in any specific case to handle
the energy of the circuit, then this length may
be divided up among two or more sets of cooper-
ating contact surfaces and these sets may be
arranged laterally of the axis of the telescoping
contacts with a great saving in space in the
length of the contacts. A specific example is a
sort of ball and socket structure wherein a plug-
like ring enters between two rows of spring fin-
gers. The total length of required contact is here
divided into two lengths, one provided by the
outer surface of the ring engaging the outer
spring fingers and the other by the inner surface
of the ring engaging the inner spring fingers.
This is one specific form of contacts herein dis-
closed. Obviously, the total length might be di-
vided into more than two parts. The disclosed
embodiment, however, illustrates the idea, which
constitutes an important feature of the present
invention.

It should also be noted that the contact ar-
rangement mentioned provides a self-centering
action and that by giving the meeting contact
surfaces a suitable curvature, there may be con-
siderable shifting of the contacts relative to their
longitudinal alignment without decreasing the
efficiency of the contact engagement as a con-
ductor of electricity. The action of the engaging
contacts is to a limited extent like that of a
universal joint. The movements take place with-
out the loss of efficiency in electrical conduc-
tivity through the joint.

Referring now to the drawings, Fig. 1 is a
front elevation of a three-phase switch con-
structed and arranged in accordance with the
present invention, certain portions being cut away
to show details of construction; Fig. 2 is an end
elevation of the same, the view being taken from
the right in Fig. 1 and showing the contacts in
closed position; Fig. 3 is a similar view, with
certain parts removed and other parts in sec-
tion, illustrating the contacts in open position;
Fig. 4 is a sectional plan view of a portion of the
structure, the plane of section being indicated
by the line 4—4 of Fig. 2; Figs. 5 and 6 are detail
views illustrating a stop employed in conjunction
with the toggle mechanism; Fig. 7 is a vertical
section through the switch parts of one phase,
the plane of section being indicated by the lines
7—7 of Fig. 1; Fig. 8 is a section of a portion of
the toggle system, the section being taken along
the arcuate section indicating line 8—8 of Fig. 2;
Fig. 9 is a vertical section illustrating one of the
spring couplings by which the bridging contact

is connected to the movable frame of the structure, the location of the section being indicated by the line 9—9 of Fig. 7, the spring of this figure occupying a natural uncompressed position; Fig. 10 is a similar view illustrating the same coupling with the parts set up so as to give the spring a given set compression; Fig. 11 is a similar view illustrating the parts as they appear when the spring is compressed beyond its given set compression, such as would occur during the operation of the switch; Fig. 12 is a similar sectional view illustrating a modified spring coupling; Fig. 13 is a similar view illustrating a further modified spring coupling; and Fig. 14 is a similar view illustrating a third modified coupling.

Throughout these views like characters refer to like parts.

As previously indicated, in the present case a three-phase switch is shown. In brief, the same comprises a main frame A, a shiftable frame B, and three contact carrying frames C, one for each phase, said frames C being connected to the frame B by three sets of spring couplings D. The result is that each frame C is yieldingly mounted upon the shiftable frame B. For each phase there is an upper insulator E, a lower insulator F, and an intermediate insulator G, telescopically arranged. The insulators E and F are both mounted on the frame A while the center insulated member G is mounted on the appropriate frame C. Associated with each set of insulators E, F, G, are corresponding contacts, H, J and K. A toggle system L serves to raise and lower the frame B together with all the parts carried by it. In open circuit position the contacts H and K are separated, while in closed circuit position they are in firm contact with each other, as clearly shown in Fig. 7.

The main frame A may be variously constructed but in the present case includes two flanged end frames 20 united by upper angle bars 21 and lower angle bars 22. These bars are secured to the end frames 20 in any suitable way as by means of bolts and nuts 23, 24, the former serving to connect the upper bars 21 and the latter the lower bars 22.

The end frames 20 are provided in their flanges with openings 25 through which securing bolts or the like may be passed into a suitable panel or other support, as will be obvious.

The frame B which is the shiftable frame of the structure, comprises angle bars 26 which extend along the front and rear of the structure in a manner similar to the bars 21, 22 of the frame A and are connected at their ends to end frames 27. The latter are provided with horizontal flanges 28 which overlie the horizontal flanges of the angle bars 26 and are secured thereto by bolts 29 or the like. The latter are provided with nuts as usual and the parts of the frame are thus firmly secured together. In its up and down travel the frame B is guided by guide rods 32 which are firmly secured to the frame A. Connection is made by passing the rods through openings in the horizontal flanges near the tops and bottoms of the end members 20 and securing the same in place by suitable nuts 33 threaded on to the ends of the rods and screwed home against the flanges. The end members 27 of the shiftable frame B have guiding sleeves 41 through which the rods 32 extend. These sleeves are of considerable length and have a sliding fit 75 on the rods. Hence a guided up and down move-

ment is provided for the frame B in its operative travels.

The frames A and B are common to the three sets of insulators and their associated contacts.

When it comes to the frames C, we have one frame for each set of insulators and contacts. Each frame C thus constitutes a mounting for the intermediate insulator G and its associated bridging contact K, or modification of that contact. Each frame C takes the form of a web 30 having an upstanding flange 31. The latter has an outline conforming to the periphery of the insulator G which, in the present case, is circular. The horizontal web portion 30 is apertured near its four corners for the passage of the bolts of the coupling devices D. The latter provide the yielding connections between the shiftable frame B and the mounting plates or members C of the different phases. Viewed in another way, each flange 31 is a supporting frame which embraces the insulator G and the portions of the web 30 which extend outward from the frame 31 and contain the apertures for the retaining bolts of the coupling devices D, are lateral projections.

Turning now to a consideration of these coupling devices, we find the same may take quite different forms. The preferred form is that illustrated in the earlier figures of the drawings, and more in detail in Figs. 9, 10 and 11. In each of these couplings there is a central bolt 34 which is threaded into an opening in the horizontal web of the angle bar 26 of the shiftable frame B. Upon this same bolt 34 is a flanged sleeved member 35 which has the interior of its sleeve 36 threaded for engagement with the threads of the bolt 34 and at its lower end is provided with the horizontal flange 37. By rotating the member 35, the same may be adjusted lengthwise of the bolt 34. The flange 37 forms a seat for the lower end of a coiled compression spring 38. The upper end of the spring bears against a flanged member 39 which has the outer surface of its sleeve 40 threaded through an opening in the web 30 of the associated contact carrying member C. The flanged member 39 moves freely up and down over the member 35 and obviously carries with it the engaged portion of the web 30. The member 39 is given an upward limiting position by means of a nut 42 which is likewise threaded upon the upper end of the bolt 34. By adjusting the nut upon the bolt 34, the position of the member 39 may be adjusted to give more or less compression to the spring 38. As clearly shown, the interior of the nut 42 is cut back on its under side, as indicated at 43, to enable the skirt 55 of the nut to pass down over the exterior of the sleeve 36 of the member 35.

In Fig. 9 the parts are shown in the position they would occupy when first assembled and before any compression is given to the spring 38. It will be noted that the upper end of the bolt 34 is also provided with an extension 44 which passes out through an opening in the head of the nut 42. As clearly shown, this extension is provided with scale markings 45. When the parts are in the position illustrated in Fig. 9, the top of the projection 44 is flush with the top of the nut 42 and the markings 45 are in their zero position.

Whenever the nut 42 is screwed down upon the bolt 34 so as to force the flanged member 39 downward to place the spring 38 under compression, then the parts assume some such position as illustrated in Fig. 10. It will be noted that in such case the projection 44 extends beyond the nut 42 and by reading that marking 45 which 75

comes nearest to the top of the nut it will be possible to know from inspection the amount of compression which is given to the spring. Thus, indicating means are provided for knowing at once the set compression.

When the switch mechanism is assembled, the four springs 38 associated with each contact carrying member C are given preferably the same degree of compression. It will be seen that if each spring be given a compression of, say, 75 pounds, then the total of the four springs would be 300 pounds for the particular member C and its associated contact.

It will be apparent from what has been said that if the member B be forced upward by the toggle mechanism L, which constitutes the operating mechanism of the switch, then the different members C would be carried upward as a unit until some resistance was encountered to cause the springs to be compressed still further. As we shall see later, this occurs when the reciprocating bridging contacts carried by the frames C meet and effectively engage the upper terminal contacts of the switch.

When the switch parts are brought into final position, then the springs 38 are compressed beyond the amount at which they have been initially set and they assume some such position as illustrated in Fig. 11. There the parts are shown in a position corresponding to the fully closed position of the switch. In changing from the position of Fig. 10 to the position of Fig. 11, the projection 44 will not be changed but it will be noted that the nut 42 will pass upward out of engagement with the member 39. The extent of this movement will show upon each coupling device that there is a pressure applied to the contacts in excess of that given the springs as an initial set. For the purpose of measuring the extent of this additional pressure, the exterior of the sleeve 38 is preferably provided with scale markings 46. By reading down upon these markings, a measured value for the extent of pressure applied by each coupling device D may be observed. If desired, these markings 46, and also the markings 45, may be carefully graduated to indicate the pressure in pounds or other convenient unit. Thus, indicating means for knowing the extent of contact pressure in addition to the set compression is provided.

Under the assumption, namely 75 pounds per spring, it will be apparent that as soon as any of the markings 46 appear by reason of the separation of the nut 42 from the sleeve 40 of the member 39, then more than 300 pounds pressure is being applied between the central contact and the upper contact, such being in the case of Fig. 7, the contacts K and H.

While on the subject of these spring coupling devices, it might be well to point out that the structure of the preferred spring means D may be modified and the modifications may be extended to include a very simple form.

Thus, in the case of the coupling D', shown in Fig. 12, the structure is the same as shown in Figs. 9, 10 and 11 except that the flanged member 39 is omitted and the upper end of the spring 38 acts directly against the under side of the web 30 of the member C. Obviously, where the member 39 is employed, it is possible to adjust the position of the member C with respect to the flange of the member 39, and thus relatively position the frames B and C, without in any way changing the initial set given to the spring 38. Of course where the member 39 is omitted this ad-

justment is not possible. However, in many cases this adjustment may not be desired. In the case of the coupling D', there are the same scale markings 45 and 46 and they serve in the same way except that the reading of the markings 46 indicates the separation between the nut 42 and the web 30, instead of between the nut and the sleeve 40 of the member 39, as in the preferred form. The actions of the parts when pressure in excess of the set amount is applied are just the same as before.

In the case of the modified coupling D², we have advanced one more step toward simplification, with a resultant omission of function. In this case, the nut 42 is replaced by the nut 48, and the bolt 34 gives place to a similar bolt 49, which is threaded, as before, into the flange 26 of the adjacent member 26 of the frame B, and which, as before, carries the flanged sleeve member 35. In this case, the spring 38 is compressed between the flange 37 of the member 35 and the under side of the web 30 of the frame C. By reason of substituting the bolt 49 for the bolt 34, there are no markings 45 to indicate the extent of initial set given to the spring 38. There are, however, markings 46 which will indicate the extent of separation between the lower surface of the nut 48 and the upper surface of the web 30. The extent of separation as indicated by this reading, will show the amount of compression in addition to the set amount, that is being applied through that particular coupling to the associated contacts.

Going still further in the direction of simplification, we have the coupling structure D³ where in the central bolt 50 has a head 51 at its lower end which bears against the under face of the flange 26 of the member B. A nut 52 is threaded on the upper end of the bolt 50 and is pressed home against a sleeve 53 which presses at its lower end against the upper face of the flange 26 and its upper end against the under face of the nut 52. When the nut is screwed down tight upon the bolt, then the parts 26, 50, 52 and 53 move together as a unit, and so long as the resistance to the movement of the frame does not exceed the amount of the set compression in the spring 38, said member will also move with the other parts. But, as soon as the resistance to the applied pressure is greater than said amount, the spring will begin to compress and the frame members B and C will be brought nearer together. In this case, scale markings 46 on the sleeve 53 may serve to indicate the amount of extra compression being applied through the associated spring. Such markings will measure the extent of separation between the under face of the nut 52 and the upper face of the web 30 of the frame C.

These various forms of couplings maintain a loose connection between the frame B on the one hand and the several insulator and contact bearing frames C on the other hand. As a result, the mountings for the bridging contacts have a floating movement upon, or relative to, the frame B and in consequence thereof the contacts readily adjust themselves to each other for good engagement.

It will also be noted that when the operating frames C are moved into the closed position, and when the pressure in the springs exceeds the set amount, say 75 pounds per spring (300 pounds per phase), then the springs shift further, as before pointed out, and there is still reserve energy stored in the springs and available to compensate for any yielding which may occur by reason of the

parts remaining under pressure over a long period of time or by reason of wear of the parts.

As previously indicated, there are three tubular telescoping insulators. The uppermost of these is the insulator E. It is the one of largest diameter and includes a skirt 56 and an apertured end 57. The outer surface of the insulator is corrugated to increase the exterior creeping surface. Near its lower end it is connected to a mounting member 54 having a vertical annular flange 55 and a web 58, said member being similar in shape and outline to the intermediate mounting member C, previously described. The four corners of the web 58 are apertured, as shown more particularly in Fig. 4, and suitable bolts 59 pass through these apertures and mating apertures in the horizontal flanges of the main frame members 21 and are provided with appropriate nuts. By screwing the latter home, the mounting 54 of each insulator E may be firmly and fixedly secured. Suitable cement 60 positioned between the insulator and the flange 55 holds the insulator in place upon the main frame A.

The insulators F at the lower portion of the switch are similar to the insulators E but of considerably smaller diameter. Each such insulator comprises a skirt 61 and an apertured head 61^a. The outer surface of this insulator is also corrugated near its lower end so as to increase the creepage surface. Connection is made between each of these insulators and the lower members of the frame A through a member 62 similar in shape to the member 54. The web portion of the member 62 is connected to flanges of the frame members 22 by suitable bolts 63 having appropriate nuts. In this instance cement 64 binds the insulator to the annular flange of the member 62 and the insulator is thus held firmly in place by attachment to the lower portion of the main frame A.

The intermediate insulators G are similarly secured by cement 64 to the vertical flanges 31 forming part of the intermediate frames C. The insulators G thus move with the frames C. As clearly shown, each of these insulators is of intermediate diameter and passes inwardly of the associated insulator E and outwardly of the associated insulator F. Each insulator G is also provided with an inwardly projecting flange 65 which serves as part of the connection with its contact K as hereinafter more fully pointed out.

When it comes to the contacts which are carried within these different insulators, different contact arrangement may be employed. In the preferred form of the invention, each of the terminal contacts H comprises a block 68 of copper or other good electric conducting material, which has a threaded shank 69 on the one side and a series of inner spring fingers 70 and outer spring fingers 71 on the other side. The shank extends upward through the aperture in the head 57 of the insulator E and is firmly secured to the insulator by a nut 72, suitable washers 73, 74 being employed to perfect the connection. An additional nut 75 is threaded on the shank 69 and serves as a binder for the electric conductor that is connected to the shank. The fingers 70 and 71 are preferably provided by cutting away the block 68 so as to provide a central space 76 and an annular space 77 and then splitting the resulting projections by longitudinal cuts so as to give the several fingers, viz., the fingers 70 on the inside and the fingers 71 on the outside. These are also preferably curved so as to provide a bell-mouthed approach, as clearly illustrated in Fig. 7. A coiled outer spring

78 extends around the outer fingers 71 and tends to force them inward. A somewhat differently coiled spring 79 extends spirally around within the space 76 and engages the inner surfaces of the inner fingers 70 and by its action tends to force these fingers outward. The spring pressed fingers 70 and 71, however, are sufficiently stiff, while yet laterally yielding, to provide the requisite space 77 for the entrance of the cooperating ring contact 95. Thus, a contact having a solid base portion and two concentric rows of contact fingers is provided. The spring fingers 70 and 71 cooperate with the space 77 between their respective rows to provide a socket for reception of the plug-like portion upon the associated bridging contact, presently to be described.

In the embodiment under consideration, each of the lower terminal contacts J is in the form of a rod 82 threaded at its lower portion and provided with retaining nuts 83, 84, the former acting on the inside of the head 61^a of the insulator F and the latter operating on the outside. Suitable washers 85, 86 are positioned between the nut 83 and the head 61^a on the one hand and the nut 84 and the head 61^a on the other hand. The extra nut 87 serves to bind the conductor, in whatever form it may be, to the terminal contact J. The latter is preferably composed of copper or other good conducting material.

Each of the intermediate contacts K is composed in this embodiment of a tube 88 which is reduced in diameter at an intermediate point and split so as to provide a series of spring fingers 89. The reduced diameter enables the spring fingers 89 to fit upon and make good contact with the lower terminal J. A series of coiled springs 90 surround the spring fingers 89 and press them inward against the surface of the rod 82 of the contact J. With this construction the tube 88 may be moved up and down upon the rod 82 and in all positions there will be good electrical engagement between the contacts.

The upper portion of the tube 88 is exteriorly threaded so as to be screwed into a contact head 91. The latter is provided with a lateral flange 92 and an auxiliary clamping ring 93. Between the flange 92 and the ring 93 is positioned the insulator flange 65. The ring 93 has threaded engagement with the outer portion of the head 91 and by screwing the ring 93 home against the flange 65, the head 91 and the tube 88, which is connected with it, are firmly secured to the intermediate insulator G. If desired, intervening washers 94 may be employed upon the upper and lower faces of the flange 65 in order to improve the mechanical connection. The upper part of the head 91 is shaped so as to provide a contact ring 95 which is solid and in cross-section has tapered surfaces similar to the surfaces of a gear tooth. This ring is adapted to pass into the annular space 77 between the spring contact fingers 70 and 71 of the upper contact H. The ring 95 thus acts as a plug and the space 77 and the associated fingers 70 and 71 cooperate to provide a socket for receiving the plug-like portion 95.

The inclined bell-shaped walls of the socket-like space 77 cooperate with the inclined walls of the plug-like ring contact 95 to provide a self-centering action of the contacts. This action is permissible because of the loose mounting of the associated frame C upon the frame B through the spring coupling means D, as before pointed out.

Besides obtaining the self-centering action, the engaging surfaces of the ring 95 and fingers 70 and 71 are such that a line contact is provided

on each side of the ring when the switch is in closed position. Not only is this true, but it is also true that such a line contact will exist even though the bridging contact be out of exact axial alinement with the upper contact. In this way a certain floating of the bridging contact is possible without destroying the line engagement of the contact surfaces. One pair of lines, an inner and an outer, will exist for each position of the parts, ranging from the central position where the axis of the intermediate contact is in exact alinement with the axis of the upper contact, on through intermediate positions in all possible vertical planes, to the extreme positions in said planes wherein the axes of the two contacts intersect at the maximum possible angle.

Again, in these several positions of the contacts, the pressure exerted upon the ring contact 95 by the associated contact fingers 70 and 71 will be approximately equal and relatively high, the total pressure being divided among the several fingers. The pressures provided by the resiliency of the fingers 70 and 71 reinforced by the action of the springs 78 and 79 cooperate with the action of the springs 39 of the couplings D to maintain the contacts in proper position and thus insure the high pressure between the conducting parts while the switch is in closed position. In practice the contacts may be so firmly pressed together that the conductor formed thereby is in electrical effect practically a continuous solid conductor. Pressures upon the contact parts in excess of that required to produce this result need not be applied. By maintaining these high pressures for all line contacts between the two conducting contacts, there is no weakening of the conducting capacity even though exact alinement be not maintained. In this way an efficient and long lived switch is provided. The material of the tubular conducting member K is also copper or other good conducting metal.

In considering this matter of line contacts between switch parts, we find the central plug-like contact 95 and the associated spring finger contacts 70 and 71 good examples. Thus, the outer surface of the ring 95 contacts with the inner surfaces of the several spring fingers 71. Because of the curvature of the contacting surfaces of each of these parts, clearly shown in Fig. 7, it follows that the portions of the surfaces thus engaging each other are in a practically continuous line around the outside of the ring 95. This line-like engagement is what is meant by a "line contact", although under pressure there might be some deformation of the parts along the contact line and thus the line might have infinitesimal width and so be a zone of infinitesimal width. The term "line contact" however is commonly used to describe this sort of engagement between switch contacts. Similarly, because of the curvatures of the inner face of the ring 95 and the outer surfaces of the fingers 70, there is a similar line contact extending around on the inside of the ring and the outside of the spring fingers 70. In this case, the sum of the lengths of these two line contacts determines the carrying capacity of the switch, as before indicated.

The mechanism for moving the shifting frame B upward and downward is found in the toggle mechanism L. This mechanism, or toggle lever system as it may be called, applies the requisite high pressure to the engaging surfaces of the contacts K and H when the switch is in fully closed position. Such mechanism includes

a longitudinal shaft 98 suitably journaled in the main frame A, crank arms 99 keyed to the opposite ends of the shaft 98, and cooperating links 100 acting between the ends of the crank arms 99 and the end members 27 of the frame B, the connection with the latter being provided through suitable pivots 101. The construction is such that the members 99 and 100 act as toggles, one at each end of the switch structure. The toggle arrangement is such that the central pivots 102 by which the arms 99 and links 100 are connected move through and slightly beyond a dead center point existing between the centers of the shaft 98 and the pivots 101. The movement of the toggle members to this over-center point brings the contacts H and K into the requisite firm engagement, as aforesaid, and then the toggles lock the switch parts in closed position. In order to properly bring about this staying of the toggle movement each end member 27 is preferably provided with a stop 103.

The stop 103 may take different forms but preferably an eccentric cam 104 is employed as illustrated more particularly in Fig. 6. This cam 104 may be held in any desired position by 25 clamping it against the face of the adjacent member 27 by any suitable means, as, for example, the bolt 105. Where the latter is used, its head may press against the cam 104 and it may be held in permanent engagement by means 30 of a nut 106 on the opposite side of the frame member 27, all as illustrated more particularly in Fig. 5.

Obviously, the actuating shaft 38 may be rotated through the requisite angle in order to bring 35 about proper opening and closing movements of the switch contacts by any suitable means. In the present instance, a lever 109 is keyed to one end of the shaft 98 in a position adjacent to one of the end members 29 of the main frame A. 40 This lever has a handle 110 at its outer end by which an operator may move it to and fro between the closed position, illustrated in Fig. 2, and the open position, wherein the lever extends downward and forward from the shaft 98. The 45 lever 109 is preferably provided with lugs 111 which are apertured and made to lie adjacent to a similarly apertured portion of the main frame, such as indicated at 112, near the lower end of the member 113, which is secured by bolts 50 114 to the adjacent portion of the main frame A, suitable spacing sleeves 115 surrounding the bolts and properly spacing the bracket member 113 from the end frame member 29. When in proper position the lever 109 may be held against 55 interference by a padlock 116 which may have its hasp passed through aligned openings in the lever 109 and the lugs 112 of the frame 113, either in the open or closed position of the switch, as desired. 60

The frame 113 is provided with a grooved channel 118 which extends in an arcuate path and provides a pathway for a retaining pin 119 carried by the lever 109. This is clearly illustrated in Fig. 8 which is a section along said arcuate pathway. A leaf spring 120 is secured at one end by pins 120^a to the face of the lever 109 and the pin 119 is secured to the free end of the spring 120 so that the same may be yieldingly moved with reference to the lever. A button 121 on the free end of the spring 120 and preferably in alinement with the pin 119 serves to draw the pin 119 out of one of two recesses 122 which it may occupy at the ends of its traverse. The 75

lever 109 is suitably recessed at 123 to provide for the in and out movement of the pin 119.

From what has been said it will be clear that the various springs 38 of the coupling devices D serve two functions. One of these is to provide the requisite pressures between the electrical switch contacts, as, for example, contacts H and K, and the other is to hold the toggles in their locking positions after they have been moved 10 to their holding positions beyond dead center, corresponding to the closed position of the switch.

As previously indicated, the contact structure and arrangement may be considerably modified. What has been described in detail heretofore 15 has included a solid lower contact and a tubular intermediate contact.

In respect to modifications of these contacts it is clear that the shapes of the coating contact surfaces may be greatly varied over those shown 20 and still get the ball and socket action and the requisite line contacts and line contact lengths for the different positions of the engaged contacts relative to each other. The different shapes of the contacting portions of the cooperating contacts will be determined by the required current carrying capacity of the switch and other characteristics, such as the shape of the insulators required to permit the proper movements of the various switch parts and the like.

30 Obviously, then, in carrying out my invention many alterations and modifications may be made in the disclosed structure without departing from the spirit and scope of the invention. I therefore aim to cover by the terms of the appended claims 35 all those alterations and modifications which rightly come within the scope of my invention.

I claim:

1. In an electric switch, cooperating electrical contacts, a relatively fixed insulating mounting for one of said contacts, a relatively movable insulating mounting for the other of said contacts, actuating mechanism for said movable mounting, a set of compression springs acting between said actuating mechanism and said movable mounting to press said contacts together when brought into engagement, means for giving said springs a variable adjustment to suitably adjust the same with a given compression whereby the movement of said actuating mechanism will 45 press said springs beyond said given compression only when the pressure between said contacts exceeds an amount corresponding to said given spring compression, and indicating means associated with each of said springs to show the extent of pressure being applied therethrough in 50 excess of said given amount.

2. In an electric switch, cooperating electrical contacts, a relatively fixed insulating mounting for one of said contacts, a relatively movable insulating mounting for the other of said contacts, actuating mechanism for said movable mounting, a set of compression springs acting between said actuating mechanism and said movable mounting to press said contacts together when brought into engagement, means for adjusting the abutting ends of said springs relative to both said actuating mechanism and said movable mounting, thereby to give said springs a set compression, and indicating means associated with each of said springs to indicate the pressure being applied therethrough in excess of said set amount.

3. In an electric switch, relatively fixed and movable suitably insulated contacts, suitable

mountings for said contacts, actuating mechanism for shifting said movable contact and mounting, a set of coiled compression springs each acting between said movable contact mounting and said mechanism, said movable contact and mechanism serving as abutment members for the spring, a bolt-like member secured at one end to one of said abutment members and movable freely through an opening in the other of said abutment members, a nut secured to the free end of said bolt-like member and serving through the intervening abutment member to limit its movement away from said spring, and means for limiting the inward movement of said nut on said bolt-like member to compress said spring with a given compression.

4. In a device of the class described, a contact carrying member, an actuating member for said carrying member, a plurality of spring mountings carried by one of said members and operating to 20 transmit motion from one to the other of said members, each said spring mounting comprising a coiled compression spring, a holding bolt secured to one of said members and passing freely through an opening in the other of said members, a nut on the free end of said bolt for limiting the movement of the adjacent member away from said spring and cooperating with said adjacent member to give said spring a definite set compression, and scale markings on said bolt for 30 indicating two things, one the set compression of the spring, and the other the extent of movement of said members relative to each other whenever said spring is compressed beyond said set compression.

5. An electric switch comprising relatively fixed and movable self-centering electrical contacts, a movable mounting for said movable contact, said mounting having lateral projections, a movable supporting frame for said mounting having portions adjacent to said projections, a set of spring couplings uniting said projections and frame with yielding connections, each coupling including a bolt secured to said frame and extending loosely through an opening in the associated projection, a coiled spring around said bolt, means on said bolt for compressing said spring with an initial pressure, said couplings being peripherally spaced about said movable contact and the springs and loose connections thereof serving to provide a floating action such as to permit said contacts to center themselves when brought together, and means for moving said frame toward and from said fixed contact.

6. An electric switch comprising two end insulating tubes, an intermediate insulating tube in telescopic relation to said end tubes, terminal electric contacts within and mechanically connected to said end insulating tubes respectively, an intermediate electric contact within and mechanically connected to said intermediate insulating tube and operative to electrically connect and disconnect said terminal contacts, a frame by which said end tubes are supported, an intermediate frame by which said intermediate tube is supported, all said tubes being in alinement, a toggle system for moving said intermediate frame to make and break circuit, and spring means operating between said intermediate frame and associated tube to yieldingly hold the toggles of said system in contact closing position and simultaneously therewith to apply a yielding pressure to the engaged contacts.

FRED FARRELL.
